SUPPORTING CLASP FOR PERSONAL WEAR

Alberto Signorini, Buenos Aires, Argentina

Application July 2, 1936, Serial No. 88,653

7 Claims. (Cl. 24—245)

The present invention relates to supporting clasps for personal wear and more particularly to clasps for supporting hose and the like articles and which comprise a rigid base member carrying a button or the like and a rigid clamping element articulated at one end to said base.

It has been proposed heretofore to couple the rigid clamping member to the base by means of a crank-type hinge-pin. This construction while generally satisfactory calls for three separate elements even for the simplest form of the clasp and furthermore involves in the process of assembling the clasp the step of rotatably securing the upper end of the rigid clamping loop to the crank-pin portion of the hinge-pin.

The object of the present invention is to provide a supporting clasp having the general advantages of the rigid type of clasp above referred to but comprising only two instead of three essential parts.

A further object of the invention is to provide a supporting clasp having a rigid base and a rigid clamping-element in which the movement and locking of the clamping member are guided and controlled by cam-slots formed in a suitable portion of the base and co-operating with integral ends projecting from the rigid clamping member.

A further object of the present invention is to provide in a clasp of the type described release means for the rigid clamping-member which shall be operable from the front of the clasp.

It is likewise an object of the present invention to provide in combination with a clasp of the kind described oscillating cam-type release means associated with the attachment portion of the clasp and adapted upon oscillation thereof to move the rigid clamping member from its locked to its released position.

Other objects and advantages of the present invention will become apparent during the course of the following detailed description.

In the drawing:

Fig. 1 is a perspective view of one embodiment of my new supporting clasp showing the clamping-member in the released position.

Fig. 2 is a front view and

Fig. 3 a side view of the upper portion of the rigid base.

Fig. 4 is a front view and

Fig. 5 a side view of the upper portion of the rigid clamping-member of my novel supporting clasp.

Fig. 6 is a perspective view of the upper form

of a preferred embodiment of the clamping-member.

Fig. 7 is a plan and

Fig. 8 a side elevation of a releasing member.

Fig. 9 is a plan showing the upper portion of the supporting clasp according to the present invention fitted with the releasing member shown in Figs. 7 and 8.

Fig. 10 is a plan of an attachment member provided with a portion of an oscillating cam-type releasing device.

Fig. 11 is a section along the line XI—XI of Fig. 10.

Fig. 12 is a plan view of the upper portion of a supporting clasp modified so as to adapt it to co-operate with the cam-type releasing means of Fig. 10.

Fig. 13 is a perspective view seen from the rear of a complete supporting clasp according to the present invention provided with oscillating cam-type releasing members, and

Fig. 14 is a plan view of the rear face of the lower end of the base of the clasp illustrating the method of forming the hook-button and retaining the rubber cushion.

With particular reference to Figs. 1 to 6 my novel supporting clasp comprises a rigid base 10 to the upper end of which is secured an attachment element 12 consisting of a frame 14 surrounding a slot 16 through which the attachment strap or tape (not shown) is intended to be passed. The other or lower end of the base is widened to form a clamping surface 18 which carries a hook-button 20 punched up from said base to form a hollow chamber within which a cushion 22 of resilient material as for example rubber is located.

The upper end of the base 10 is likewise enlarged to provide a platform 24 from the upper edge of which a pair of arms 26 extend upwardly 40 parallel to the longitudinal axis of the base, the inner sides of said arms thus defining a substantially rectangular recess 28. Along the outer edge of each arm and of each side of the platform 24 extends a bent-up wall 30 having a 45 substantially arcuate cam-slot 32. These walls 30 project at right angles to the base in the same direction as the hook-button 20, and the cam slots are so positioned in said walls that one end thereof lies in the neighborhood of the upper 50 corner of the wall nearest to the platform while the other end lies in the neighborhood of the lower free corner of the wall the slots curving convexly towards the upper free corners.

Said slots are adapted slidably to receive lat- 55

erally projecting pins 34 provided on either side of the narrowed down neck portion 36 of the rigid clamping loop 38. The width of said neck portion 36 is such that it may freely move into and out of the space defined between the two walls 38. For convenience of operation there is provided on said neck portion 36 a still narrower upwardly extending finger piece 40 of width such as to allow it to pass freely between the arms 28 and into the rectangular recess 28 when the clamping member is in clamping position. As may be seen in Figs. 5 and 6 said finger piece 40 is formed so as to provide a rearwardly projecting portion 40a which is designed to lie substantially in the same plane as the rear face of the base 10 when the clamping-member is in clamping position.

In the embodiment shown in Fig. 5 the projection is formed by rolling over the top of the finger piece 40 and the blank may be so cut that this rolled over portion has formed in it the laterally projecting pins 34. Alternatively, a piece of stiff wire of suitable length may be soldered to the rear face of the clamping member immediately below said rolled over portion although it is to be understood that such a method of construction is not preferred, inasmuch as it necessitates three parts to make the complete supporting clasp, namely, the base stamping, the clamping-member stamping and the wire for the pins.

The preferred embodiment of the clamping-member is illustrated in Fig. 6 in which the pins 34 are formed mid-way of the finger piece and the upper end of the finger piece is bent back substantially at right angles to form the rearwardly extending projection 40a, the free corners of which may advantageously be rounded. In this form the clamping member lends itself readily to incorporation in the simple type of supporting clasp illustrated in Fig. 1 and moreover can with only minor modifications be used as well for the constructional variants shown in Figs. 9, 12 and 13.

In the embodiment illustrated in Figs. 1, 2 and 3 the attachment member 12 is permanently and rigidly secured to the base by means of the depending curved joining-members 42 the ends of which remote from the attachment element merge into the upper ends of the arms 28. If desired, the joining-members may have their lower portions bent at an angle with respect to the plane of the attachment element, as indicated in Fig. 1, so as to cause the attachment element to lie substantially in the mid-plane of the assembled clasp or even in a plane parallel to the base and tangent to the free edges of the walls 38.

It will be observed that a space 44 having rounded ends and a width slightly greater than that of the recess 28 is provided between the joining-members 42. In the modification shown in Fig. 9 this space is utilized to accommodate the head 46 of a releasing member 48 (Figs. 7 and 8) which has depending from its lower edge an extension 58 of width substantially equal to that of the neck portion 36 of the clamping-member and provided at the mid-point of its lower free edge with a rearwardly offset tongue 52 and with laterally projecting pivots 54. To accommodate these pivots the side-walls 31 of the modification illustrated in Fig. 9 are extended towards the attachment-member and are conveniently perforated to provide bearing holes for said pivots. The rearwardly offset tongue 52 is

adapted to engage with a rectangular slot 56 (Fig. 6) provided for this purpose in the free edge of the rearwardly extending projection 40a of the clamping-member so that when the clamping-member is in clamping position, said projection 40a will push said tongue 52 towards the rear and consequently maintain the head 46 of the releasing member in a slightly forward position with respect to the attachment member 12. In order to release the clasp pressure may be applied from the front thereof to the head of said releasing member which will thereupon swing about its pivots and by the engagement of the tongue with the projection 40a will move the upper portion of the clamp away from the base 10 under the guidance of the cam-slots 32. As soon as the pins 34 of the clamping-member have moved along said slots sufficiently for a force parallel to the base to become unrestrictedly operative, the rubber cushion 22 of the button 20 will, owing to its resilience and the fact that it is designed to be compressed by the inner edge 58 (Fig. 1) of the lower cross-bar 60 of the clamping-member when the latter is in clamping position, give rise to a snap-action release of said clamping-member.

In the modification shown in Fig. 13, the details of which are illustrated in Figs. 10, 11 and 12, the attachment element 12a is connected to the base 10b by means of a cam-plate 62 attached permanently and rigidly to the supporting member by means of depending joining members 42a similar to the joining members 42 of Figs. 1, 2 and 9. Said cam-plate 62 has a recess 64 formed in the lower portion thereof and is provided at each end of its lower free edge with a cam tooth 66 coplanar with the floor 68 of said recess 64. The recess 64 is bounded on the side nearest to the attachment element by a substantially semi-circular arc and is perforated at a point corresponding to the centre of the corresponding circle for the purpose hereinafter explained.

In this embodiment the upper end of the base 10b (Fig. 12) is modified by providing a coupling platform 70 which bridges the two arms 28 above the rectangular recess 28 and is, on the side remote from said recess, bounded by a substantially semi-circular arc. A perforation 72 is provided in the platform 70 substantially at the centre 50 of the circle corresponding to said arc and similar to the perforation 74 of the cam-plate 62. The platform is adapted to fit into the recess 64 of said cam-plate and the base 10b is adapted to be pivotally connected to said cam-plate as, for example, by means of a tubular rivet indicated at 76 in Fig. 13 which passes through the perforations 72 and 74. The proportions of the parts are such that, in the assembled condition of the supporting clasp and with the clamp 38 in clamping position, the projection 40a thereof will extend between the two cam teeth 66 of the cam-plate 62, as best seen in Fig. 13. It will be clear to those skilled in the art that if under these conditions the base be rocked about the pivot 76 with respect to the attachment element one or other of the teeth 66 will engage with the corresponding curved free corner of the projection 40a and will thereby force the upper portion of the clamping loop forwardly with respect to the base, thus giving rise to the same type of snap-release as is obtained by use of the releasing-member of Fig. 9.

As previously stated the button 20 is preferably punched up from the material of the clamping-

surface 18 and in the hollow space thus provided the rubber cushion 22 is accommodated. This cushion can, by adopting the construction just described, be conveniently introduced into said hollow space from the rear and in order to prevent it from dropping out accidentally the blank for the base is designed to have wings 18 projecting from the clamping-plate portion and terminating in a circular, semi-circular or 10 rectangular or the like head 80. After insertion of the rubber cushion the said wings are bent over through two right-angles as indicated in dotted lines in Fig. 13 and clearly shown in Fig. 14 to lie against and slightly compress with their 15 heads 80 the said cushion 22.

What I claim is:

1. A supporting clasp for articles of personal wear comprising a rigid base, an attachment element secured to said base, a hollow hook-button on the end of the base remote from said attachment element, a cushion of resilient material within said hook-button, an enlarged portion at the end of said base remote from said hook-button, a pair of parallel arms extending 25 from the transverse free edge of said enlarged portion and defining between them a substantially rectangular recess, a wall extending along each of the lateral edges of said enlarged portion and along the outer edges of said arms, said walls projecting at right angles to said base on the same side thereof as said hook-button, a curved cam slot in each wall, a rigid clamping member having an end adapted to engage said hook-button and provided at its opposite end 30 with a reduced neck portion of width such as to allow said neck portion to move freely into and out of the space between said walls, said neck portion having on each lateral edge thereof an outwardly directed pin extending freely into the 35 corresponding cam slot.

2. A supporting clasp for articles of personal wear comprising a rigid base, an attachment element secured to said base, a hollow hook-button on the end of the base remote from said attachment element, a cushion of resilient material within said hook-button, an enlarged portion at the end of said base remote from said hook-button, a pair of parallel arms extending 45 from the transverse free edge of said enlarged portion and defining between them a substantially rectangular recess, a wall extending along each of the lateral edges of said enlarged portion and along the outer edges of said arms, said walls projecting at right angles to said base on the same side thereof as said hook-button, a curved cam slot in each wall, said slot extending substantially from the corner of said wall remote from the hook-button and nearest the 50 arm to the diagonally opposite free corner of the wall and being convexly curved towards the remaining free corner, a rigid clamping member having an end adapted to engage said hook-button and provided at its opposite end with a reduced neck portion of width such as to allow 55 said neck portion to move freely into and out of the space between said walls, said neck portion having on each lateral edge thereof an outwardly directed pin extending freely into the corresponding cam slot.

3. A supporting clasp for articles of personal wear comprising a rigid base, an attachment element secured to said base, a hollow hook-button on the end of the base remote from said 60 attachment element, a cushion of resilient ma-

terial within said hook-button, an enlarged portion at the end of said base remote from said hook-button, a pair of parallel arms extending from the transverse free edge of said enlarged portion and defining between them a substantially rectangular recess, a wall extending along each of the lateral edges of said enlarged portion and along the outer edges of said arms, said walls projecting at right angles to said base on the same side thereof as said hook-button, a 10 curved cam slot in each wall, a rigid clamping member having an end adapted to engage said hook-button and provided at its opposite end with a reduced neck portion of width such as to allow said neck portion to move freely into and 15 out of the space between said walls, said neck portion having on each lateral edge thereof an outwardly directed pin extending freely into the corresponding cam slot, and a finger plate of reduced width extending away from said hook-button engaging end, said finger piece having on the face thereof which in the assembled condition of the clasp is nearest to the base, a projection adapted to lie in said rectangular recess when the clamping member is in clamping 20 position.

4. A supporting clasp for wearing apparel comprising a rigid base, having at one end a hollow hook-button and at the other end an enlarged portion, an attachment element rigidly secured to said base, a hollow hook-button on the end of the base remote from said attachment element, an enlarged portion at the end of said base, a pair of parallel arms extending 25 from the transverse free edge of said enlarged portion and defining between them a substantially rectangular recess, a pair of joining members depending from said attachment element and merging into said arms, said joining members defining between them an opening of 30 greater width than that of said recess, a wall extending along each of the lateral edges of said enlarged portion and along the outer edges of said arms, said walls projecting at right angles to said base on the same side thereof as said 35 hook-button, a curved cam slot in each wall extending from a point thereof near said enlarged portion towards the free corner of the wall nearest to the hook-button and curving convexly away from said base, a bearing-hole 40 in the wall near the remaining free corner thereof, a releasing member including a head adapted to fit freely in said opening and a depending narrower platform having a rearwardly offset tongue depending centrally from its transverse 45 free edge and laterally projecting pivots journaled in said bearing-holes, a clamping member having at one end a button engaging end and provided at its opposite end with a reduced neck 50 portion allowing said neck portion to move freely 55 into and out of the space between said walls, a pin projecting outwardly from each lateral edge of the neck portion and extending freely into the corresponding slot and a finger piece of reduced width extending away from said button-engaging end, said finger piece having in the face thereof nearest to the base a projection with a central notch adapted to receive the tongue of the releasing member when the clamping member is in clamping position.

5. A supporting clasp for wearing apparel comprising a rigid attachment element including a hollow elongated frame and a cam plate depending centrally from one of the longer sides of the frame, and having at each end of its 60

transverse free edge a projecting coplanar cam tooth, a rigid base carrying a hook-button near one end and having at its other end an enlarged portion, a pair of parallel arms extending from the transverse free edge of the enlarged portion and defining between them a substantially rectangular recess, a platform bridging said arms at the free ends thereof, and pivotally mounted on said cam plate, a wall extending along each of the lateral edges of said enlarged portion and along the outer edges of said arms, said walls projecting at right angles to said base on the same side thereof as said hook-button, a curved cam slot in each wall curving convexly away from said base on the same side thereof as said hook-button, a curved cam slot in each wall curving convexly away from said base, a rigid clamping member having a hook-button engaging end and provided at its opposite end with a reduced neck portion adapted to move freely into and out of the space between said walls, pins projecting outwardly from each lateral edge of the neck portion and extending freely into the corresponding slots, and a finger piece extending away from said hook-button engaging end and having a projection with curved free corners adapted to lie in said recess between said cam teeth when the clamping member is in clamping position.

6. A supporting clasp for wearing apparel, comprising a rigid attachment element including a hollow elongated frame and a cam plate depending centrally from one of the longer sides of the frame, a recess formed in the portion of the cam-plate remote from said frame and having a semi-circular boundary, a cam tooth projecting from each end of the free edge of said cam-plate and coplanar with the surface of said recess, a rigid base having a hook-button near one end, an enlarged portion at the other end, a pair of parallel arms extending from the transverse free edge of the enlarged portion and defining between them a substantially rectangular space, a platform bridging said arms at the free ends thereof, the edge of the platform remote from said rectangular recess being adapted to fit said semi-circular boundary, said platform

being concentrically pivoted in said recess, a wall extending along each of the lateral edges of said enlarged portion and along the outer edges of said arms, said walls projecting at right angles to said base on the same side thereof as said hook-button, a curved cam slot in each wall curving convexly away from said base, a rigid clamping member having a hook-button engaging end and provided at its opposite end with a reduced neck portion adapted to move freely into and out of the space between said walls, a pin projecting laterally from each outward edge of said neck portion and extending freely into the corresponding slots, and a finger piece extending away from said hook-button engaging end and having a projection with curved free corners adapted to lie in said recess between said cam teeth when the clamping member is in clamping position.

7. A supporting clasp for articles of personal wear comprising a rigid base having at one end an enlarged clamping surface and at the opposite end an enlarged portion, a pair of arms extending from said enlarged portion and directed away from said clamping surface, a wall perpendicular to the plane of the base extending along the outer free edge of the arms and the lateral free edge of the enlarged portion, an arcuate cam slot in said walls, a rigid clamping member having a neck portion adapted to move freely between said walls, a pin projecting laterally from each side of the neck portion and extending into said arcuate slots, a hook-button pressed up from the material of said clamping surface and extending from the same side of the base as said walls, relatively narrow wings extending in a substantially radial direction from said clamping surface and terminating in a head, and a resilient cushion located within said hook-button, said wings being in the assembled condition of the clasp bent over through two right angles to bring the head thereof into compressive contact with said cushion.

ALBERTO SIGNORINI.
